UNITED STATES PATENT OFFICE.

GEORGE P. WARTCHOW, OF MINOT, NORTH DAKOTA.

SADDLE FOR MAINS.

1,354,359.

Specification of Letters Patent.

Patented Sept. 28, 1920.

Application filed March 23, 1920. Serial No. 368,058.

To all whom it may concern:

Be it known that I, GEORGE P. WARTCHOW, a citizen of the United States, residing at Minot, in the county of Ward, State of North Dakota, have invented certain new and useful Improvements in Saddles for Mains; and I do hereby declare the following to be a full, clear, and exact description of the invention, such as will enable others skilled in the art to which it appertains to make and use the same.

This invention relates to water distribution, and more especially to mains and pipes; and the object of the same is to produce a saddle which will protect the service cock and will serve as a support for the pipe or casing through which a key may be inserted to close the cock.

When it is desired to lead a service pipe from a main into a house or other point where water or gas is to be used, the main is tapped (usually in the side) and a service cock screwed into the hole and closed, and from this cock the service pipe is led and is later connected with the plumbing of gas system, the service pipe having its own cut-off cock within the dwelling. This service cock in cities is usually at or near the curb line and is surmounted by a curb box having a cover at the ground level, so that the authorities may lift the cover and insert a key and close the cock to cut off the water at a point as near the main as possible. In smaller cities and towns the main may not be so deep and the corporation cock is not always so well protected, and it is the purpose of the present invention to provide a device in the nature of a saddle which can be clamped over the main and which has one end shaped so as to protect this cock, as the device will sustain a considerable load in case the same should be thrown upon it by vehicles passing over the main, perhaps when the soil was soft.

Details are set forth below and shown in the drawings wherein:

Figure 1 is a perspective view from what might be called the front side of the main showing the entire structure in place.

Fig. 2 is a perspective view from the rear side, the upper portion of the casing being broken away and the key shown ready to be inserted.

Fig. 3 is a perspective view of the saddle inverted.

Fig. 4 is a sectional detail showing the service cock tapped into the main.

The letter M designates in the present instance a water main, and C is a service cock which has been tapped into one side of the same and from which is to be led a service pipe as indicated in Fig. 1 at P.

This invention consists primarily of a saddle having a body 1 cut out or arched on its under side so as to fit closely over the upper half of a main of that size to which it is adapted, its rear end being carried down in a single leg or toe 2 having a set screw 3 which can be tightened up against the main, and its front end being carried down and forked so as to produce arms 4 spaced sufficiently to straddle the cock C without touching the same. These arms are substantially triangular in side view, and are connected by a web 5 forming a continuation of the body, which web and the arms collectively constitute a three-sided inclosure for the cock and the parts above it. The web carries an upstanding sleeve 6, and into this sleeve is inserted the lower end of a pipe 7 which is secured within the sleeve as by lead packing 8, calking, or a screw joint. Over the upper end of the pipe 7 is slipped another pipe 9, preferably having a cap 10 at its top which will stand at or near the level of the ground.

No novelty is claimed for the cock C, but as usual it is of the globe-valve type, its plug having a web 11 across its upper end. A key stem 12 is disposed between the arms 4, transversely notched as at its lower end at 13 to fit over said web, and preferably held thereon by means of a pin 15 passing across the stem and through the web. The body of the stem rises through the casing and its sleeve, and may be squared at its upper end as shown at 16. In Fig. 2 is shown the ordinary key 17 consisting of a long shank with a handle at its upper end and a head 18 at its lower end having a squared socket to fit 100 on the squared end 16 of the key stem.

In the use of this device, the ground is dug away down to the main, the latter tapped and the cock inserted and closed, and the service pipe led away from the cock. The key stem is now applied and fastened to the web of the cock. The saddle is next put in place over the key stem, its arms passed down astride the cock, and the set screw in its toe tightened. Now the casing 110

is inserted within the sleeve 6 and calked, screwed or packed at 8, the casing rising to a point about level with the ground, and its cap 10 applied. Thereafter the excavation 5 can be filled in and tamped, and later the plumber can lead the service pipe P to the cutoff valve in the dwelling, and connect it with the system in the latter. When the dwelling is ready for occupancy, the city or 10 town authorities open the cock C and the fluid begins to flow. If now at any time, by reason of the failure of the house owner to pay his water bill, or on account of scarcity of water in the supply system, leakage 15 in the service pipe, or for any other reason where the action of the cut-off valve in the house would not be sufficient, it becomes necessary or desirable to cut off the flow of water as near the main as possible, the cap 10 is removed and a key 17 is run 20 down through the casing until its head 18 engages the squared upper end 16 of the key stem, and when the latter is turned for a quarter revolution the cock is closed. If the 25 leak or other difficulty had been at a point quite near the main or cock, the water could thus be cut off from the surface without the necessity of digging down through the wet ground and against the upward flow of the 30 leaking water (or gas), so that the advantage of cutting off the flow before opening up the ground at all is obvious. But in the ordinary use of the device, the presence of 35 the saddle over the main and with its arms astride the key stem and cock, affords a protection for these parts of the water system, because the saddle if properly made and applied will sustain a very heavy weight. Also its sleeve 6 affords a support 40 for the casing through which the key is to be inserted, whether said casing is at the curb line or not or whether it rises completely to the surface or not. The structure 45 will be by preference made of rough casting, and in sizes adapted to mains of various gage.

What is claimed as new is:

1. The herein described saddle for mains comprising a casing arched on its under 50 side to fit over the main and having a single toe at one end and spaced arms at the other end, a web connecting the upper end of

said arms and with them forming a cavity, and a set screw threaded inward through said toe.

2. The herein described saddle for mains 55 comprising a casing arched on its under side to fit over the main and having a single toe at one end and spaced arms at the other end, a web connecting the upper end of said arms and with them forming a cavity, a sleeve rising from said web, and means through said toe for clamping the saddle on the main.

3. The combination with a main, and a 60 cock tapped into one side of the same; of a saddle whose body is arched to fit over the main, one end having arms spaced to pass astride said cock, and means on the other end for tightening the saddle in place.

4. The combination with a main, and a 65 cock tapped into one side of the same and having a web at the upper end of its plug; of a saddle arched to fit over the main and forked at one end to stand astride said cock, the top of the fork having an upstanding 70 sleeve, a casing rising from the sleeve and adapted to permit the insertion of a key, and a key stem secured to said plug and rising through said sleeve and made angular at its 75 upper end for engagement by said key. 80

5. The combination with a main, a cock in one side of the same, and an upright key stem connected with its plug and rising above the main and squared; of a saddle 85 whose body extends across the main and is arched on its lower side to fit over the same, one end of the body having depending arms spaced to stand astride said key stem and cock, a web connecting the upper ends of said arms, a sleeve rising from said web around 90 the stem, a set screw through the other end of the saddle against the main opposite said cock, tubular casing packed into the sleeve and rising therefrom to a point near the earth's surface, and a cap for closing its 95 upper end.

In testimony whereof I affix my signature in the presence of two witnesses.

GEORGE P. WARTCHOW.
